To all whom it may concern:

Be it known that I, EDWARD G. WATKINS, of Gardner, in the county of Worcester and State of Massachusetts, have invented and 5 produced a new and original Design for Cane Fabric, of which the following is a specification.

Reference is to be had to the accompanying drawing, forming a part of this specification, which shows a piece of cane fabric with my design applied.

The leading feature of my design consists in the arrangement of the parallel stripes *a* of contrasting color from the body of the 15 fabric, said stripes being alternately interrupted upon their corresponding margins to show the body of the fabric in each stripe in a staggered line of checks.

f represents a piece of cane fabric bearing my design, consisting of the parallel colored stripes *a*, the body of the fabric showing through said stripes as a staggered row of checks.

I claim—

The design for cane fabric, as herein shown and described.

In testimony whereof I have signed my name to this specification, in the presence of two subscribing witnesses, this 18th day of November, A. D. 1896.
